CLAIM

The ornamental design for a bottle jack, as shown and described.

DESCRIPTION

FIG. 1 is a top, front, right side perspective view of a bottle jack of the inventive subject matter.

FIG. 2 is a top plan view thereof.

FIG. 3 is a bottom plan view thereof.

FIG. 4 is a front elevation view thereof.

FIG. 5 is a rear elevation view thereof.

FIG. 6 is a left side elevation view thereof; and,

FIG. 7 is a right side elevation view thereof.

The broken lines showing the various aspects of the bottle jack represent unclaimed portions of the design.
